(57) **CLAIM**

The ornamental design for a panel, as shown and described.

DESCRIPTION

FIG. 1 is a front perspective view of a panel showing my new design according to a first embodiment.

FIG. 2 is a rear perspective view of the panel of FIG. 1.

FIG. 3 is a front view of the panel of FIG. 1.

FIG. 4 is a bottom view of the panel of FIG. 1.

FIG. 5 is a first side view of the panel of FIG. 1.

FIG. 6 is a second, opposite side view of the panel of FIG. 1.

FIG. 7 is a rear view of the panel of FIG. 1.

FIG. 8 is a top view of the panel of FIG. 1.

FIG. 9 is a front perspective view of a panel according to a second embodiment.

FIG. 10 is a rear perspective view of the panel of FIG. 9.

FIG. 11 is a front view of the panel of FIG. 9.

FIG. 12 is a bottom view of the panel of FIG. 9.

FIG. 13 is a first side view of the panel of FIG. 9.

FIG. 14 is a second, opposite side view of the panel of FIG. 9.

FIG. 15 is a rear view of the panel of FIG. 9.

FIG. 16 is a top view of the panel of FIG. 9.

FIG. 17 is a front perspective view of a panel according to a third embodiment.

FIG. 18 is a rear perspective view of the panel of FIG. 17.

FIG. 19 is a front view of the panel of FIG. 17.

FIG. 20 is a bottom view of the panel of FIG. 17.

FIG. 21 is a first side view of the panel of FIG. 17.

FIG. 22 is a second, opposite side view of the panel of FIG. 17.

FIG. 23 is a rear view of the panel of FIG. 17; and,

FIG. 24 is a top view of the panel of FIG. 17.

The panel is shown with symbolic break lines in its length in the third embodiment. The appearance of any portion of the article between the break lines forms no part of the claimed design.

1 Claim, 12 Drawing Sheets
